UNITED STATES PATENT OFFICE.

HENRY CURTIN, OF LITTLE FALLS, NEW YORK.

CIRCULAR-KNITTING MACHINE.

SPECIFICATION forming part of Letters Patent No. 402,906, dated May 7, 1889.

Application filed January 21, 1889. Serial No. 296,960. (No model.)

To all whom it may concern:

Be it known that I, HENRY CURTIN, of Little Falls, in the county of Herkimer, in the State of New York, have invented new and useful 5 Improvements in Circular-Knitting Machines, of which the following, taken in connection with the accompanying drawings, is a full, clear, and exact description.

This invention relates to the class of knitting-machines in which the knitting-needles are carried on a rotary cylinder and receive a reciprocating motion by cams sustained stationary at the outside of the needle-cylinder.

The chief object of this invention is to afford access to the aforesaid cams, when required for repairs or adjustment, without necessitating the removal of the needles; and to that end my invention consists in the improved construction and combination of 20 parts hereinafter fully described, and specifically set forth in the claims.

In the accompanying drawings, Figure 1 is a vertical transverse section of the cam-rings and their support, with the upper portion of 25 the needle-cylinder broken away to better illustrate the aforesaid parts. Fig. 2 is a vertical transverse section of one side of the needle-cylinder, cam-rings, and support of the latter; and Fig. 3 is a top plan view of the 30 aforesaid parts.

Similar letters of reference indicate corresponding parts.

B represents the base or bed plate of the machine. I denotes the driving gear-wheel, 35 which is arranged horizontally under the bed-plate and has its hub fitted in a downward-projecting cylindrical bearing, B', formed on the bed-plate.

A represents the needle-cylinder, which is 40 firmly secured to the hub of the gear-wheel I, so as to rotate with the same. One of the needles is shown at a in Fig. 2 of the drawings. The shank of each of the needles is provided with an outward-projecting portion, 45 a', which engages at opposite ends with cams c c, attached to rings P P', surrounding the needle-cylinder. By means of said cams the needles are caused to successively reciprocate during the rotation of the needle-cylinder, in the usual and well-known manner.

In order to afford ready access to the cams

c c, when required for repairs or adjustment, I support the cam-rings P P' independently of each other, and preferably by dividing each of said rings into two or more segmental sections, as at d d in Fig. 3 of the drawings, and detachably securing the said rings, respectively, to the top and bottom of an annular plate, D, which surrounds the needle-cylinder, and is supported on standards C C, secured to and rising from the bed-plate B.

In order to allow the plate D to be raised or lowered, and thus support the cam-rings P P' at the desired elevation to move the needles the desired distance above the needle-cylinder during the rotation of the latter, I firmly attach to the top of the standards C C screw-threaded posts C' C', and mount thereon nuts n n, which are formed with upward-projecting cylindrical necks o o, and with 70 horizontal shoulders o' o' at the bases of said necks. The plate D is provided with eyes e, which closely embrace the necks o o, while the said plate rests on the aforesaid shoulders. Above the plate D are nuts n' n', applied to 75 the posts C' C' and bearing on top of said plate.

The cam-rings P P' are preferably attached to the intervening plate D by means of screws i i, which are removable and thus allow either of the cam-rings P P' to be detached from the plate D when desired.

Having described my invention, what I claim as new, and desire to secure by Letters Patent, is—

1. In combination with the rotary needle-cylinder, a plate arranged stationary around the exterior of said needle-cylinder, and the lower cam-ring, P', hung on said plate.

2. In combination with the rotary needle-cylinder, a plate arranged stationary around the exterior of said needle-cylinder, and the lower cam-ring, P', divided transversely and hung on the aforesaid plate, as and for the purpose set forth.

3. In combination with the bed-plate and needle-cylinder, standards rising from the bed-plate, a plate surrounding the needle-cylinder and supported on the standards, and the cam-rings P P', secured, respectively, to 100 the top and bottom of the aforesaid plate, as and for the purpose set forth.

4. In combination with the bed-plate and needle-cylinder, the standards C C, rising from the bed-plate, the screw-threaded posts C' C', attached to the standards, nuts n n' on 5 said posts, the plate D, supported between said nuts, and the cam-rings P P', secured, respectively, to the top and bottom of the plate D, substantially as described and shown.

5. In combination with the bed-plate and 10 needle-cylinder, the standards C C, rising from the bed-plate, the screw-threaded posts C' C', attached to said standards, the nuts n, provided with the cylindrical necks o and shoulders o', the plate D, provided with eyes 15 e, closely embracing the necks o and seated upon the aforesaid shoulders, the nuts n', applied to the posts C' C' above the plate D, and the cam-rings P P', secured, respectively, to the top and bottom of said plate, substantially 20 as described and shown.

6. In combination with the bed-plate and needle-cylinder, standards rising from the bed-plate, the plate D, surrounding the needle-cylinder and supported on the aforesaid standards, and the cam-rings P P', composed 25 of segmental sections secured to the top and bottom of the plate D, substantially as described and shown.

In testimony whereof I have hereunto signed my name, in the presence of two witnesses, at Little Falls, in the county of Herkimer, in the State of New York, this 15th day of January, 1889. 30

HENRY CURTIN. [L. S.]
